UNITED STATES PATENT OFFICE.

HENRY M. GLEASON, OF WATERBURY, CONNECTICUT, ASSIGNOR TO CHASE COMPANIES INC., OF WATERBURY, CONNECTICUT, A CORPORATION.

SORTING MACHINE.

Application filed August 10, 1922. Serial No. 580,867.

To all whom it may concern:

Be it known that I, HENRY M. GLEASON, a citizen of the United States, residing at Waterbury, in the county of New Haven and State of Connecticut, have invented a new and useful Improvement in Sorting Machines; and I do hereby declare the following, when taken in connection with the accompanying drawings and the characters of reference marked thereon, to be a full, clear, and exact description of the same, and which said drawings constitute part of this application, and represent, in—

Fig. 1 a view in side elevation of an improved sorting mechanism embodying my invention.

Fig. 2 a view thereof in rear elevation, looking in the direction of the arrow "A" on Fig. 1.

Fig. 3 a plan view thereof, looking in the direction of the arrow "B."

Fig. 4 a detached reverse plan view of one of the dials.

Fig. 5 a detached plan view of one of the dial pocket-plates.

Fig. 6 an enlarged broken plan view of that portion of one of the dials from which the pins are discharged in systematic end presentation.

Fig. 7 a sectional view on the line 7—7 of Fig. 6.

Fig. 8 a broken edge view in elevation, looking at the dial shown in Fig. 6 in the direction of the arrow "C" thereon, a portion of the machine-frame being shown in section.

Fig. 9 a similar but less comprehensive view, showing how the selecting plunger fails to select a pin when the same is presented coil-end foremost.

My invention relates to an improved sorting mechanism primarily designed for sorting and systematizing safety-pins, preparatory to feeding them into a carding, or other, mechanism, but not so limited, the object being to produce a relatively simple, reliable mechanism constructed with particular reference to having a large capacity for work, and to demanding the minimum outlay for attention, maintenance and repair.

With these ends in view, my invention consists in a sorting mechanism having certain details of construction as will be hereinafter described and particularly pointed out in the claims.

As herein shown, the machine chosen for the illustration of my invention has six dials 10, of which three are frictionally coupled one above the other to a driving-shaft 11, and the remainder to a corresponding driving-shaft 12, the said shafts being arranged parallel and tilted from the vertical, so that the dials are positioned or inclined to rotate about midway between the vertical and the horizontal. The two upper dials are supported by and rotate upon a cross-bar 13 extending between the side-pieces 14 of the machine-frame; the two intermediate dials rest and rotate upon a corresponding cross-bar 15, and the two lower dials upon a corresponding cross-bar 16. The said cross-bars 13, 15 and 16 are formed with bosses 17 providing bearings for the said shafts 11 and 12, each of which carries at its lower end a worm-wheel 18 respectively meshing into worms 19 mounted on a transverse shaft 20 driven from any convenient source of power, not shown.

Each of the said inclined dials rotates within a fixed annular hopper-base 21, from which a concentric hopper 22 rises. The said hopper-bases 21 are formed on their lower sides with lugs 23 receiving bolts 24, by means of which they are fastened to the cross-bars 13, 15 and 16. The upper sides of the hopper-bases are also formed with lugs 25 receiving bolts 26, by means of which they are secured to cross-pieces 27 secured to arms 28 offsetting rearwardly and upwardly from the side-pieces 14 of the machine-frame.

Each dial is provided with a superimposed dial pocket-plate 29 formed in its periphery with a continuous circle of regularly-spaced, laterally-opening safety-pin receiving-pockets 30, the forward ends of which are shaped to form pin-reversing hooks 31, while their rear walls 32 are made straight. These pockets are made a trifle longer than the length of the safety-pins, which the machine is designed to sort and systematize.

Each hopper-base is formed in the left-hand side of its lower portion with a clearance-cut 33 for the reception of the upper or receiving ends of two chutes 34 and 35, as clearly shown in Figs. 3 and 6. The straight upper end of the upper chute 34 overlaps the dial pocket-plate with just enough clearance for the same to turn under 310

it, while the enlarged upper end or mouth of the lower chute 35 is arranged below the plane of the upper chute 34, in the plane of the pocket-plate, and therefore in registration with the pockets 30 therein, as shown in Fig. 8, the bottoms of these pockets being formed by the dial itself.

Each dial is provided with as many lifting or selecting plungers 36 as its pocket-plate has pockets, these plungers being positioned to rise through the plate adjacent to the forward ends of its respective pockets. Each of the said plungers is reduced at its upper end to form a transversely arranged, flattened lifting-finger 37, while its projecting lower end is provided with a rounded operating-head 38, furnished with an abutment-collar 39 supporting the lower end of a helical spring 40, the upper coil of which rests against the underface of the dial, the said spring exerting a constant effort to maintain the face of the lifting-finger 37 at the upper end of the plunger, flush with the bottom of its pocket, in which position the collar 39 of the plunger rests upon the upper face of the forked end of a bracket 41 secured by screws 42 to the lower face of the dial. The sides of the head 38 of the plunger are flattened to fit into the forked end of the bracket, so as to prevent the plunger from rotating, whereby the lifting-finger of the plunger is maintained in its transverse relation to the axis of the pocket in which it functions.

For the successive operation of the plungers 36, as the dials revolve, I employ, in conjunction with each dial, a lifting-cam 43 secured by screws 44 to the respective cross-bars 13, 15 and 16, the cams having slots 45 to provide for their adjustment, and hence for the timing of the mechanism.

These cams are respectively positioned substantially beneath the upper ends of the upper chutes 34, so as to successively lift the plunger 36 for lifting and so selecting so many of the safety-pins 45 as are presented head foremost into position to be entered into the said upper chutes 34, clear of the pockets 30 containing them, whereby the pins are permitted to fall by gravity into the upper ends of the chutes, as shown in Fig. 8. In the described action of the plungers, they engage with the lower faces of the sheet-metal clips forming the head-ends of the pins.

So many of the pins of the mass of pins riding upon the constantly rotating pocket plates of the dials as enter the pockets 30, with their coil-ends foremost, escape the above described selecting action of the plungers 36, which idly rise within the side wires or reaches of the pins without disturbing the same in their pockets, as clearly shown in Fig. 9. The pins so presented are, therefore, carried beneath the overlapping

upper ends of the upper chutes 34 into registration with the enlarged upper ends or mouths of the lower chutes 35, which are positioned, as shown in Fig. 6, in the clearance-slots 33, so as to register with the lateral openings of the pockets 30 in the pocket-plates of the dials. The pins so presented are now reversed end for end, by turning, as upon centers, upon the reversing-hooks 31 of the plates, as shown in Fig. 6, whereby they fall into the lower chutes 35, with their head-ends foremost. Two streams of pins, arranged with their head ends foremost, are thus fed from each dial into the chutes thereof.

In order to prevent the mass of pins upon any dial from banking up around the entrances to the chutes, I preferably employ some sort of a fender in the form of a partition plate 47 secured at its ends to the hopper 22 of the dial.

To avoid breakage in case of jamming, the dials are, by preference, frictionally coupled to their shafts by any suitable means, such, for instance, as by radially splitting the dial-hub to form halves 48 and 49 connected by binding-screws 50, which may be set to secure any desired frictional grip of the dials upon the shafts. The dial pocket-plates 29 are employed to simplify the production of the pockets 30, which might, of course, be formed directly in the upper faces of the dials.

While the machine herein shown is provided with six dials, this number may be increased or decreased as desired, each dial, together with its chutes and coacting parts, constituting a unitary mechanism complete in itself. While the mechanism shown and described is adapted for sorting safety-pins, it is apparent that by slight modifications of form, but without change in principle, it may be adapted to sort and systematize a great variety of similar articles.

I claim:

1. A sorting mechanism having an inclined revolving dial provided in the periphery of its upper face with a continuous series of laterally opening pockets, of a hopper, and two chutes, one of which has its mouth located above the plane of the said pockets and the other of which has its mouth in the said plane.

2. A sorting mechanism having an inclined revolving dial provided in the periphery of its upper face with a continuous series of laterally opening pockets, of a hopper, an upper and a lower chute, of which the upper has its mouth located above the plane of the said pockets, and of which the lower has its mouth in the said plane, a series of selecting plungers corresponding in number to the pockets carried by the dial in which they are positioned to enter the forward ends of the pockets, means for success-

sively operating the said plungers as they approach the upper chute, and reversing means for coaction with the lower chute.

3. A sorting mechanism having an inclined revolving dial, a pocket-plate superimposed thereupon and formed in its periphery with a continuous series of laterally opening pockets, a hopper, an upper chute, the mouth of which overlaps the dial, selecting means for the upper chute, and reversing means for the lower chute.

4. A sorting mechanism having an inclined revolving dial provided in its upper face with a continuous series of laterally opening pockets having hooked forward ends, a hopper, an upper chute, selecting means for delivering certain contents of the pockets into the said upper chute, and a lower chute positioned to receive certain other contents of the pockets as they are reversed, end for end, by the said hooks in gravitating out of the lateral openings of the pockets.

5. A sorting mechanism having an inclined revolving dial provided in its upper face with a continuous series of laterally opening pockets, a hopper, an upper chute, the mouth of which overlaps the dial, selecting means for the said upper chute, a lower chute the mouth of which is positioned adjacent to the edge of the dial, and reversing hooks located at the forward ends of the said pockets for reversing, end for end, into the lower chute, such contents of the pockets as are not discharged into the upper chute.

35 6. A sorting mechanism having an inclined revolving dial provided in the periphery of its upper face with a continuous series of laterally opening pockets, a hopper, an upper chute the mouth of which overlaps the edge of the dial, a lower chute having its mouth co-incident with the plane of the said pockets, means for discharging the contents of the pockets into the respective chutes in accordance with their end-for-end presentation therein, driving means for the

dial, and a safety friction-coupling between the dial and such driving means.

7. A sorting machine having a plurality of inclined dial shafts, a plurality of dials frictionally mounted upon each shaft, a hopper and two chutes for each dial, a series of laterally opening pockets formed in the periphery of each dial, and means for selecting the contents of the pockets and discharging them into the said chutes in accordance with their end-for-end presentation in the pockets of the dials.

8. A sorting mechanism having an inclined dial provided with a continuous series of pockets, of a hopper, two chutes, and means assisted by gravity for selecting the contents of the said pockets and discharging them into the respective chutes, in accordance with their end-for-end presentation in the pockets into which they are fed by gravity due to the inclination of the dial.

9. A sorting mechanism having an inclined revolving dial provided with a continuous series of pockets, of a hopper, two chutes one of which has its mouth located above the plane of the said pockets, selecting mechanism for delivering certain contents of the pockets into the chute having its mouth above the plane thereof, and selecting and reversing mechanism for the other chute.

10. A sorting mechanism having an inclined dial, a pocket-plate superimposed thereupon and formed in its periphery with a continuous series of pockets, a hopper, an upper chute the mouth of which overlaps the dial, selecting means for the upper chute and selecting and reversing means for the lower chute.

In testimony whereof, I have signed this specification in the presence of two subscribing witnesses.

HENRY M. GLEASON.
